UNITED STATES PATENT OFFICE.

FREDERICK S. KLUG AND CHARLES E. FREELAND, OF WHEELING, WEST VIRGINIA.

ROLL-POLISHER.

1,327,919.

Specification of Letters Patent. Patented Jan. 13, 1920.

Application filed April 8, 1919. Serial No. 283,467.

To all whom it may concern:

Be it known that we, FREDERICK S. KLUG and CHARLES E. FREELAND, citizens of the United States of America, and residents of 5 Wheeling, county of Ohio, and State of West Virginia, have invented certain new and useful Improvements in Roll-Polishers, of which the following is a specification.

This invention relates broadly to roll polishers, and more specifically to an apparatus for maintaining the surfaces of the rolls of a rolling mill in smooth and polished condition.

The primary object of the invention is to 15 provide a simple and reliable mechanism for continuously subjecting the rolls of sheet and tin plate mills to the action of abrading blocks whereby the normal true and even contour of the surfaces of the rolls is preserved and whereby scale and foreign matter is prevented from accumulating on said surfaces.

A further object is to provide an apparatus of the character mentioned which is so 25 located with respect to the rolls that its use in no wise interferes with the normal operation of said rolls.

A still further object of the invention is to 30 provide a roll polisher embodying a polishing block or stone and mechanism whereby said stone is actuated to travel back and forth from end to end of the roll and including positive and reliable means for automatically effecting reversal of the direction 35 of travel of said stone.

With these and other objects in view, the invention resides in the features of construction, arrangement of parts and combinations of elements which will hereinafter be 40 exemplified, reference being had to the accompanying drawings, in which—

Figure 1 is a front elevation of a set of rolls showing our invention applied thereto;

Fig. 2 is an end elevation of the same;

Fig. 3 is an enlarged section on line 3—3, Fig. 1;

Fig. 4 is a section on line 4—4, Fig. 1;

Fig. 5 is an enlarged detail view illustrating the brake structure;

Fig. 6 is an enlarged sectional elevation on line 6—6, Fig. 1;

Fig. 7 is an enlarged top plan view of the stone holder with a stone mounted therein;

Fig. 8 is a sectional elevation showing the

operative connection between the clutch-shaft and the upper feed-screw; and—

Fig. 9 is a detail view of the joint between the sections of the shiftable rod.

Referring to said drawings, in which like designating characters distinguish like parts throughout the several views—

1 and 2 respectively indicate the upper and lower rolls of a rolling mill, the same being mounted in housings 3 and 4, as ordinarily. Mounted upon the outer face of 65 one of said housings, as the left housing 3, is a suitable bracket 5 in which are formed bearings for two parallel shafts 6 and 7, the shaft 6 being a short constantly driven countershaft having its inner end suitably 70 journaled in a bearing (not shown) provided on the adjacent housing, and the shaft 7 being a clutch shaft which has its inner end journaled in a bearing 8 provided therefor in or on said housing. 75

The countershaft 6 carries upon its projecting outer end a pulley wheel 9 connected by a belt 10 to a suitable source of motive power, as to the coupling box 11 which connects the lower roll 3 to an adjacent set 80 of rolls. Said countershaft also carries thereon between the bearing provided therefor on the bracket 5 and the adjacent side of the housing 3 two relatively spaced pinions 12 and 13, of which the pinion 12 occupies a position in mesh with a gear 14 loosely carried by the clutch-shaft 7. The pinion 13 is disposed in mesh with an idler gear 15 which is in turn disposed in driving relation to a gear 16 that is also loosely 85 mounted on the clutch-shaft.

A clutch 17 having its opposite faces dentated is splined on the shaft 7 between said gears 14 and 16 and is adapted for interengagement with the corresponding dentated 95 faces of said gears, being shiftable from one operative position to the other for alternately connecting said gears and consequently, for effecting reversal of the direction of rotation of said shaft 7. 100

Coupled to the inner end of said clutch-shaft 7 is one end of a feed-screw 18 which extends transversely between the housings 3 and 4 adjacent to the upper roll 1 and has its opposite end journaled in a suitable bearing (not shown) formed on or in the housing 4. A block holder 20 is mounted for travel upon said feed-screw, a threaded eye 21 be-

ing provided therein in which said screw is received. Said holder has a shouldered seat 22 formed on its inner face, upon which a block 23 of carborundum, emery, or other suitable abradant material rests, the latter being held in place upon said seat by means of an overlying clamping member or plate 24 which is pivoted or hinged at one end upon an end of said holder 20 and which has a slot 25 formed in its opposite end for the reception of a threaded stud 26 carried by the corresponding end of said holder. As is obvious, said plate 24 may be swung on its pivot to and from overlying relation to the block or stone 23, as when stones are being removed or inserted, and the plate is secured in clamping relation to the stone by tightening a thumb-nut 27 carried by said stud 26.

20 Suitably mounted on the back of the holder 20 adjacent to the upper edge thereof are anti-friction rollers 28 which, during travel of the holder, traverse the face of a horizontally disposed channel bar 29 that 25 has its opposite ends mounted upon the upright inner end members 30^a of oppositely disposed angular levers 30 whereby regulatable tension is exerted for pressing the face of the block or stone 23 against the roll 1. 30 Each of said levers 30 extends outward close to the inner face of the adjacent housing and is supported by an integral laterally disposed trunnion 31 removably mounted on a U-shaped seat 32 carried by said housing. A retractile coil spring 33 has its lower end attached to the outer end of said lever 30 and its upper end adjustable with respect to a suitable support or bracket, as 34, formed on the adjacent housing. As is obvious, an adjustable yielding tension is exerted by said springs 33 which act through the levers 30, the channel bar 29, the anti-friction rollers 28 and holder 20 for regulating the pressure applied by the stone to 45 the surface of the roll.

Operatively associated with the clutch 17 is an upright shifting yoke 35 which has its lower end pivotally mounted upon a suitable fixed part of the structure, as upon the lower inwardly directed arm of the bracket 5. Pivotal connected to said clutch-shifting yoke at a suitable distance above the pivotal mounting of the latter is one end of a longitudinally shiftable reverse rod through 55 which force is exerted for effecting clutch-shifting movement of said yoke, as will hereinafter be described. Said rod, which is composed of two sections 36 and 36^a which are suitably coupled as shown in Fig. 9, is 60 disposed adjacent and parallel to the feed-screw 18 and has its opposite ends slidably supported in suitable bearings (not shown) provided therefor on the housings. The coupling for the sections of said rod is adjacent to the inner face of the housing 3 and

provides for ready removal of the section 36 when occasion requires. Fixed collars 37 are carried by the rod section 36 at suitable points adjacent to the housings 3 and 4, respectively, and located inward with respect to each of said collars and separated therefrom by a compression spring 38 is a loose collar or movable buffer plate 39. In operation, as the traveling block holder approaches one or the other limit of its movement on the screw 18, an arm 40 carried thereby engages the adjacent buffer plate 39 and carries the same therewith, compressing the spring 38 between it and the adjacent fixed collar 37. When compression of said spring has reached a certain limit a sufficient force is exerted upon the reverse rod to overcome the braking resistance to longitudinal movement of said rod offered by a suitable brake, whereupon said spring 38 acts to forcibly thrust said rod to its opposite limit of movement, swinging the yoke 35 on its pivot, whereby the clutch is shifted from one operative position to the other for effecting reverse of the direction of rotation of the feed-screw and, consequently, reversal of the direction of travel of the block holder.

The brake hereinbefore referred to comprises a spring-pressed pin 41 located transverse to the rod section 36^a and having a beveled or rounded point adapted to seat in either of two notches 42 provided therefor in said rod section; said notches being spaced relatively to receive said pin at the opposite limits of movement of the reverse rod for holding the clutch in operative relation to the gears 14 and 16. The tension of the spring 43 acts upon said pin 41 for maintaining the latter seated until such time as sufficient force is stored in the spring 38 through compression of the latter to effect a complete shifting movement or thrust of the reverse rod and, consequently, of the clutch 17, from one limit of movement to the other. Said spring 43 is disposed within a suitable casing 50 which is mounted upon the lower arm of the bracket 5, and the pin 41 is disposed for free movement through the end of said casing.

A second block holder 20' is mounted for travel upon a feed-screw 18' located adjacent to the lower roll 2 and is adjusted with respect to said roll through the intermediacy of mechanism, including springs 33', precisely similar to that employed in connection with the holder 20. Said screw has an extension 7' carrying a fixed sprocket wheel 44 which is driven from a similar sprocket 45 carried by the clutch-shaft 7 through a sprocket chain 46 connecting said sprockets. As is obvious, reversal of the direction of travel of the feed-screw 18' is accomplished through said connecting means simultaneously with reversal of the screw 18. In

other words, the arrangement is such that the movements of the two block holders 20 and 20' are accomplished in unison.

As is best shown in Fig. 7, each of the 5 block holders may carry adjacent to each of its ends a brush 47 of suitable stiff material, as wire, which acts upon the feed screw for removing dirt or other foreign matter from the bottoms of the threads or convolutions thereof.

10 The clutch shaft 7 at its point of coupling to the feed-screw 18 is formed with a shouldered enlargement 7^a the shoulder of which is designed to interengage with a shoulder 15 48 formed on the bearing 8, whereby is prevented outwardly directed end thrust which might otherwise result, in case of accident or breakage of rolls, in disarranging the driving mechanism.

20 A shield or guard-plate 49 is preferably mounted in overhanging relation to each feed-screw whereby the dropping of bars or sheets upon said screw or upon the stone holder is prevented.

25 A sheave 51 is disposed to exert regulatable yielding pressure on the belt 10 whereby the latter is kept sufficiently tight to maintain its power transmitting relation to the parts connected thereby, said sheave being 30 mounted upon an arm 55 carried by a rotary shaft 52 mounted on the housing 3 and having an arm 53 to which is connected one end of a retractile spring 54 having suitable means of tension adjustment.

35 A hand lever 56 is preferably mounted upon the clutch yoke 35 at a suitable point, as shown in Figs. 2 and 3, whereby said yoke may be shifted by hand, as when it is desired to shift the clutch to and from 40 neutral position.

What is claimed is—

1. A roll polisher comprising a feed screw, a polishing block mounted for travel on said screw, means including a shiftable 45 clutch for driving said screw, a longitudinally shiftable rod located parallel to said screw and operatively connected with said clutch, a buffer including a compression spring arranged on said rod adjacent to each 50 end of said screw and adapted to be engaged and to be compressed by said block in the direction of travel of said block as the latter approaches the end of its traverse, and a brake for resisting shifting movement 55 of said rod until sufficient force is stored by compression in said buffer spring to forcibly thrust said rod, when released by the brake, from one limit of movement to the other for producing a complete shifting movement 60 of the clutch and a resultant reversal of said screw.

2. A roll polisher comprising a feed screw, a polishing block, a holder for said block mounted for travel on said screw,

means including a shiftable clutch for driving said screw, a longitudinally shiftable rod located parallel to said screw and disposed in shifting relation to said clutch, a pair of buffers disposed in spaced relation on said rod, each of said buffers including a 70 compression spring, an arm carried by said block holder for engagement with one of said buffers adjacent to each end of the traverse of said holder, and means maintaining said rod stationary until the buffer spring 75 has been sufficiently compressed in the direction of movement of said holder to store in the latter a force which, upon release of said rod, acts to thrust the rod from one limit of movement to the other in the direction of movement of said holder, whereby said clutch is completely shifted for reversing the direction of rotation of the screw.

3. A roll polisher comprising a polishing block, a holder for said block, mechanism 85 whereby said holder is actuated to travel longitudinally of the roll, means actuated by said holder adjacent to each of its limits of travel whereby its direction of travel is reversed, anti-friction rollers carried by the 90 outer face of said holder, a pivoted member resting against said rollers and adapted to be traversed by the latter during travel of said holder, said member being wholly independent of said holder and means for adjusting the pressure exerted by said member upon said holder through said rollers for regulating the pressure of said block 95 upon the roll.

4. In a roll polisher, a holder having a 100 threaded eye and provided with a shouldered seat for the reception of a polishing block, and a clamping member mounted on said holder, said member having one end pivoted to said holder and being adapted for movement to and from a position in overlying clamping relation to a block mounted on 105 said seat.

5. In a roll polisher, a holder having a 110 threaded eye and provided with a shouldered seat for the reception of a polishing block, means for clamping said block upon said seat, anti-friction rollers carried on the back of said holder, a member resting against said rollers and adapted to be traversed by the latter during travel of said holder, and means whereby the pressure of said member upon said holder through said rollers may be adjusted for regulating the pressure of the block upon the roll.

In testimony whereof we affix our signatures in presence of two witnesses.

FREDERICK S. KLUG,
CHARLES E. FREELAND.
